(57) **CLAIM**

The ornamental design for a brush suction head for a cleaning appliance as shown and described.

DESCRIPTION

The patent or application file contains at least one drawing executed in color. Copies of this patent or patent application publication with color drawing(s) will be provided by the Office upon request and payment of the necessary fee.

1.1 is a front view of a first brush suction head for a cleaning appliance, showing the new design;

1.2 is a rear view thereof;

1.3 is a left view thereof;

1.4 is a right view thereof;

1.5 is a top view thereof;

1.6 is an enlarged top view thereof;

1.7 is a bottom view thereof;

1.8 is an enlarged bottom view thereof;

1.9 is a front, top perspective view thereof;

1.10 is a rear, bottom perspective view thereof;

1.11 is another front, top perspective view showing a variation state thereof;

2.1 is a front view of a second brush suction head for a cleaning appliance, showing the new design;

2.2 is a rear view thereof;

2.3 is a left view thereof;

(Continued)

2.4 is a right view thereof;
2.5 is a top view thereof;
2.6 is an enlarged top view thereof;
2.7 is a bottom view thereof;
2.8 is an enlarged bottom view thereof;
2.9 is a front, top perspective view thereof;
2.10 is a rear, bottom perspective view thereof; and
2.11 is another front, top perspective view showing a variation state thereof.

The portions of the brush suction head for a cleaning appliance shown by coloring with yellow form no part of the claimed design.
